CLAIM

The ornamental design for an adapter for telecommunications terminals, as shown and described.

DESCRIPTION

FIG. 1 is a front and upper right perspective view of an adapter for telecommunications terminals showing my new design;

FIG. 2 is a rear and upper right perspective view thereof;

FIG. 3 is a rear and upper right perspective view of an adapter for telecommunications terminals showing a second embodiment of my new design. Except for the rear appearance, the plan and elevational views are the same as the first embodiment;

FIG. 4 is a rear and upper right perspective view of an adapter for telecommunications terminals showing a third embodiment of my new design. Except for the rear appearance, the plan and elevational views are the same as the first embodiment;

FIG. 5 is a right side elevational view of an adapter for telecommunications terminals showing the first embodiment of my new design, the left side elevational view thereof being a mirror image;

FIG. 6 is a top plan view thereof;

FIG. 7 is a front elevational view thereof; and,

FIG. 8 is a bottom plan view thereof.

FIG. 1

FIG. 2

FIG. 3

FIG. 4

FIG. 5

FIG. 6

FIG. 7

FIG. 8
